UNITED STATES PATENT OFFICE.

MICHAEL MILLETT, OF OMAHA, NEBRASKA.

LUBRICATING DEVICE FOR THE SURFACES OF LOCOMOTIVE DRIVING-BOXES.

No. 860,818.

Specification of Letters Patent.

Patented July 23, 1907.

Application filed August 4, 1906. Serial No. 329,204.

To all whom it may concern:

Be it known that I, MICHAEL MILLETT, a citizen of the United States, residing at Omaha, in the county of Douglas and State of Nebraska, have invented certain new and useful Improvements in Lubricating Devices for the Surface of Locomotive Driving-Boxes, of which the following is a specification.

My invention relates to a new and useful lubricating device for the surface of locomotive driving boxes and driving wheel hubs, and has for its object to provide an inexpensive, durable and efficient device of this character, which will be effective for the purpose designed.

A further object is to provide a device whereby the lubricant is fed automatically from the reservoir through the wall of the driving box to the surface thereof and then instantaneously distributed thereupon by the hub of the driving wheels; said lubricant being in a constant state of agitation and being conveyed from the reservoir to the surface to be lubricated by reason of the lateral movement and constant jar of the locomotive when in motion.

A still further object is to provide a device of this character whereby the lubricant cannot seep to the surface of the driving box when the locomotive is not in motion, thereby creating a great saving of lubricant.

A still further object of my invention is to provide a lubricating means for the surface of locomotive driving boxes, which will be possessed of extreme simplicity and be easily and inexpensively applied to any locomotive driving box or trailer box now in use, thus rendering the invention practical and useful.

With these and other objects in view as will pertain to a device of this character, my invention consists in the novel construction and arrangement of parts, which will be hereinafter fully described and pointed out in the appended claims.

Referring to the accompanying drawings wherein like characters of reference denote similar parts throughout the several views:—Figure 1 is a central sectional view of a locomotive driving box with portions thereof broken away, clearly showing the arrangement of the several parts showing my invention. Fig. 2 is a view looking in direction of the arrow in Fig. 1. Fig. 3 is a side elevation of the valve-stem. Fig. 4 is an end view of the head thereof. Fig. 5 is an end view of the shank of the valve-stem. Fig. 6 is an enlarged end view of the head of the valve-stem in section on line X—X of Fig. 3 looking in direction of the arrow. Fig. 7 is a detail in section of the horizontal opening in the wall of the driving box, and Fig. 8 is a fragmentary view showing the front surface of the locomotive driving box.

Referring to the drawings 1 designates a locomotive driving box and 2 the oil or lubricant chamber or reservoir which is formed into the top of all locomotive

driving boxes. The wall 3 of the driving box 1, it will be observed is provided with the horizontal opening or passage 4 which leads from the reservoir to the surface to be lubricated; the end leading to the surface 60 to be lubricated being of conical form and being formed with the annular shoulder 5 at the base of the conical shaped portion, the object of which will be described hereinafter.

My invention which is adapted to be applied to 65 any locomotive driving box now in use, comprises a valve-stem 6 which is essentially of circular form in cross section having portions thereof at its rear cut away to form a triangular end 7; the opposite end of the valve-stem being enlarged as at 8 and formed 70 with a circular groove as at 9 to form a seating in conjunction with the shoulder 5, of the passage 4, the remaining portion of the head being formed of conical contour, the periphery thereof being cut away at a plurality of places as at 10 to form flat surfaces which 75 prevent any cutting or grinding of the head with the conical surface 4, of the horizontal passage 4. The angular end of the shank in conjunction with the walls of the opening through the apertured plug 11 provides a plurality of spaces 12, leading from the 80 reservoir to the feed chamber 13, which is formed in the horizontal opening 4 and between the plug 11, and the surface 14 to be lubricated. Through these openings 12, lubricant may pass to the feed chamber 13 where it is held until it is forced to seep from the 85 feed chamber 13, to the surface 14 to be lubricated, which it is caused to do automatically, owing to the lateral movement and constant jar of the engine when in motion.

In applying my invention to a locomotive driving 90 box, I first place a coiled spring 15 made of fine spring wire around the shank 6 of the valve-stem and then place the latter into the horizontal opening 4, as clearly shown in Fig. 1; when this has been done I pass the angular end 7, of the shank 6 through the opening of 95 plug 11 and then by means of a wrench, I screw the plug 11 to the position as shown in Fig. 1, thus allowing a portion of the shank to project into the reservoir.

The coiled spring 15 before being coiled is covered or provided midway of its ends with a piece of sheet 100 lead or the like 15 to form a weight for the spring, so that it will have a tendency to work the spring with the least jar of the engine, thus imparting a reciprocating motion to the valve-stem thereby opening and closing the feed opening and conveying lubricant to 105 the surface to be lubricated. The end of the spring engaging the head of the valve is soldered to the head as at 16 so that whenever the spring vibrates due to the constant jar of the engine when in motion, the head of the valve-stem will reciprocate and alternately open 110 and close the feed opening.

The operation is as follows: When the locomotive is

in motion, there is a constant jar, which mechanics term the lateral motion of the engine; this it should be observed tends to impart a reciprocating motion to the valve-stem due to the fact that the spiral or coiled 5 spring is not of sufficient strength to resist the lateral movement or constant jar of the engine when in motion; consequently the lubricant is caused to seep from the feed chamber 13 between the outer surface of the tapered head 8 and the conical surface of the opening 10 4 and to find an outlet through the small opening 17 to the surface 14, to be lubricated. It will readily be seen that the shoulder 5, when the valve-stem is in a reciprocating motion is not permanently engaged with the seating 9 of the head 8 thus allowing lubricant to 15 seep from the feed chamber to the surface 14. The flat portion 10 with which the tapered portion of the head 8 is provided, allows the lubricant to easily work its way to the surface 14 and further should any sand, dirt or any extraneous matter become lodged or in any 20 way come in contact with the surface of the tapered head, it would not cut or grind as these flattened places 10, provide an orifice or opening which communicates with the chamber 13, when the shoulder is not in engagement with the seating 9, thus allowing the sand 25 or dirt to work its way into the feed chamber and prevent cutting of the conical head or opening. After the lubricant has been conveyed to the surface 14, it is evenly and instantaneously distributed thereupon by means of the hub of the driving wheel. To assure 30 the more even distribution of the lubricant upon the surface 14, I provide the same with a pair of grooves 16', radiating from the opening 17 as clearly shown in Fig. 8, which grooves always carry a supply of lubricant for the surface of the hub of the driving wheels 35 to distribute when the locomotive is in motion, it being understood that no lubricant can seep its way to surface 14 when the engine is at rest, since the spring 40 yieldingly holds the seating 9 of head 8 in engagement with shoulder 5, thus closing communication with surface 14.

In Figs. 1, and 2, I have shown a V-shaped groove 18, the purpose and function of which is to feed the lubricant to passage 4, when the level of the former has descended beneath the point of location of the 45 lowermost space 12.

Having thus fully described my invention; what I claim as new and desire to secure by Letters Patent is:—

1. In combination with a locomotive driving-box provided with a lubricant reservoir and a passage connecting the reservoir with the surface of said box, a sliding valve in said passage, and a spring for controlling said valve, said spring being of increased weight at its central portion.
2. In combination with a locomotive driving-box pro-

vided with a lubricant reservoir and a passage connecting 55 the reservoir with the surface of said box, a controlling valve in said passage, and a coiled spring surrounding said valve and having its central coils of increased weight as compared with the remainder thereof.

3. In combination with a locomotive driving-box provided with a lubricant reservoir and a passage connecting the reservoir with the surface of said box, an apertured plug closing one end of said passage, a valve having a valve-stem passed through said plug aperture, a head on said valve, and a coiled spring between said head and plug, 60 65 said spring being centrally weighted.

4. In combination with a locomotive driving-box provided with a lubricant reservoir and a passage connecting the reservoir with the surface of the said box, an apertured plug closing one end of said passage, a valve, a stem for the valve having cut-away portions on the end extending through the plug aperture, a coiled spring surrounding said stem and secured at one end to the valve head and at the opposite end abutting said plug, and a weight on the 70 75 spring at points intermediate its length.

5. In combination with a locomotive driving box having an oil reservoir and a passage connecting said reservoir with the surface of the box, an apertured plug at the juncture of said reservoir and passage, a spring pressed valve in said passage having a stem projecting in said aperture of said plug, said stem having cut-away parts at points where it passes through said plug aperture, a head on said valve, said head being conical and having a circular groove 80 85 therein and being formed with flat surfaces on its conical portion.

6. In combination with a locomotive driving box having an oil reservoir therein and a passage connecting said reservoir with the surface of said box, said box surface being formed with grooves which lead into said passage, and a spring held displaceable valve in said passage, having a tapered head formed with cut-away parts. 90

7. In combination with a locomotive driving box having an oil reservoir therein and a passage leading from said reservoir to the surface of said box, said passage adjacent said surface of the box being formed with a conical depression having an annular shoulder at its base, and a spring pressed valve in said passage having a conical head normally seating in said depression and having an annular groove to receive said shoulder. 95

8. In combination with a locomotive driving box having 100 an oil reservoir therein and a passage leading from said reservoir to the surface of the box, said passage adjacent said surface of the box being formed with a conical depression having an annular inwardly projecting shoulder at its base, and a valve in said passage having a conical 105 head seating in said depression, said valve having an annular groove receiving said shoulder and having a plurality of flat surfaces on its conical head.

9. In combination with a locomotive driving box having 110 an oil reservoir therein communicating with the surface of the box, means for controlling the egress of the oil to said surface, and means for movably mounting said means, said mounting means embodying a resilient element weighted to assist the displacement thereof.

In testimony whereof I affix my signature in presence 115 of two witnesses.

MICHAEL MILLETT.
